UNITED STATES PATENT OFFICE.

GEORGE E. BULL, OF MONESSEN, PENNSYLVANIA, ASSIGNOR TO PITTSBURGH STEEL COMPANY, OF PITTSBURGH, PENNSYLVANIA, A CORPORATION OF PENNSYLVANIA.

CRIMPING MACHINE.

Application filed December 4, 1922. Serial No. 604,809.

To all whom it may concern:

Be it known that I, GEORGE E. BULL, a citizen of the United States, and resident of Monessen, in the county of Westmoreland 5 and State of Pennsylvania, have invented a new and useful Improvement in Crimping Machines; and I do hereby declare the following to be a full, clear, and exact description thereof.

10 My invention relates to crimping mechanism for forming crimps in wire or other forms of metal, and such mechanism is particularly well adapted for forming crimps in the stay-wires of a fabric composed of 15 strand and stay-wires welded, or otherwise secured, at their points of intersection, where such fabric is to be employed in connection with plaster or stucco work as a reinforcement, the crimps acting to space the 20 fabric from the framework so that when the plaster or stucco is applied it will completely envelop the fabric.

The object of my invention is to provide 25 a machine by which such crimps may be formed in the stay-wire of such a fabric without distorting the fabric, as by forming wavy irregularities along its edges, due to the taking up of the wire of the stays in forming the crimps.

30 To these ends my invention consists, generally stated, in first forming a crimp at a point intermediate the ends of the stay-wire, and then successively forming crimps in both directions from said first crimp to 35 the ends of the wire.

In the accompanying drawing, Fig. 1 is 40 a side elevation partly in section, of a machine for forming fabric of strand and stay-wires electrically welded at their points of intersection, and showing my invention applied thereto; Fig. 2 is an enlarged plan view of the crimping mechanism; Fig. 3 is an enlarged detail of a pair of the crimping dies with the wire in position for crimping; 45 Fig. 4 shows the dies closed; Fig. 5 is an enlarged sectional detail of the crimping dies and the cam-mechanism for operating same; and Fig. 6 shows a portion of the fabric after the crimps have been formed in the 50 stay-wires thereof.

In the drawings, I have illustrated a machine for forming a fabric composed of strand and stay-wires electrically welded at their points of intersection, said machine 55 being known as the Perry machine illus-

trated and described in Letters Patent of the United States, No. 813,823, February 27, 1906, but as said machine is merely used for illustrative purposes it has not been deemed necessary to illustrate the same in detail but 60 only in diagrammatic form.

The numeral 2 designates a suitable frame having guide-rolls 3 which feed the strand-wires in position to be acted on by the welding dies 4 and 5, said feed being intermittent 65 to allow for the welding to take place at fixed intervals. The movable dies 4 are mounted on flexible leads 6, and said dies are advanced by spring-actuated plungers 7. The stay-wires 8 are fed by suitable mechanism 70 into holders 9 and are picked out of said holders by fingers 10 and lowered into position to be engaged by the movable dies 4. Transformers 11 are provided and electrical connections for welding the wires electrically at the points of intersection when 75 the welding dies are brought into engagement with each other.

The fabric composed of the stay-wires 8 and strand-wires 12, so formed, is engaged 80 by the guiding and straightening sheaves 13 mounted on the shaft 14, there being one sheave for each strand-wire, intermittent movement being imparted to said sheaves by the ratchet and pawl 15 and 16.

In the rear of the sheaves 13, and below the same, is located my improved mechanism for crimping the stay-wires 8. Adjusting screws 19 engage the stationary dies 17 for adjusting same.

Movable female dies 20 are adapted to co-operate with the stationary dies 17, and said movable dies are mounted to move in guides 21. Each movable die 20 has the idle roller 22 mounted at its outer end, and each of said rollers is engaged by a disc 23 provided with the cam 24 mounted on the shaft 25. The cam-discs 23 are secured to the heads 26 of the drums 27 spaced at intervals on the shaft 25, and in order to provide for the adjustment of said cam discs 23, the said discs are provided with the slots 28 engaged by bolts 29 on the heads 26.

The cam-discs 23 have their cam-faces 24 so arranged with reference to each other 105 that the central cam disc 23^a will act to advance its corresponding die 20 before any of the other dies are operated, and the remaining cam-discs on each side of the central cam-disc 23^a have their cam-faces so ar-

ranged, as indicated in Fig. 5, that said cam-discs will act successively on their corresponding dies for the purpose more fully hereinafter set forth.

5 The shaft 25 is driven by the chain-belt 30 engaging a sprocket-wheel 31 on said shaft, said chain-belt being connected up to a sprocket-wheel 32 on the driven shaft 33, the shaft 25 being timed to operate when the 10 feed of the fabric is interrupted for the welding operation to take place.

Guide-rolls 34 direct the finished fabric to the bundling-roll 35.

In the operation of the crimping apparatus, the fabric as it is formed is fed intermittently, and the feed is so arranged that the stay-wires 8 come into position to be crimped at each movement of the fabric, so that the crimping takes place at the same time that the stay-wire is being welded to the strand-wires. When a stay-wire comes in position between the dies 17 and 20, the central cam-disc 23^a, as shown in Fig. 5, has its cam-face 24 just in position to engage 20 the idle-roller 22 of the movable die, and as 25 said cam-disc rotates the movable die is forced inwardly and in conjunction with the die 17 forms a crimp 8^a in the stay-wire. Just previous to the disengagement of the 30 cam-face of the cam-disc 23^a from the roller 22, the two cam-discs one on each side of said central cam-disc come into play and crimps are formed in the stay-wire. This

action proceeds in connection with the other cam-discs which operate in succession outwardly until all of the cam-discs have formed their respective crimps in the stay-wire. In this manner provision is made for forming the crimps in the stay-wire from the central crimp outwardly in succession, thereby preventing the distortion of the fabric by drawing in the outside strand-wires in such a way as to form a wavy line along the outer edges of the fabric, which would be the result if all the crimps were formed 45 simultaneously.

What I claim is:

1. In mechanism for forming crimps in a wire or other shape, the combination of a plurality of sets of cooperating dies, means 50 for operating one set of dies intermediate the ends of the wire, and means for operating the remaining sets of dies successively on each side of said first set.

2. In mechanism for forming crimps in a wire or other shape, the combination of a plurality of sets of cooperating dies, cams 55 adapted to engage the movable members of said dies, the cam of one of the intermediate dies arranged to operate first, and the remaining cams at each side of said first-named cam being arranged to engage their dies successively.

In testimony whereof I, the said GEORGE E. BULL, have hereunto set my hand.

GEORGE E. BULL.
